(57) **CLAIM**

The ornamental design for a light holder as shown and described.

DESCRIPTION

FIG. 1 is a perspective view of a light holder according to my new design;

FIG. 2 is a bottom perspective view thereof including an enlargement;

FIG. 3 is a left side view thereof;

FIG. 4 is a right side view thereof;

FIG. 5 is a front view thereof;

FIG. 6 is a rear view thereof;

FIG. 7 is a top view thereof;

FIG. 8 is a bottom view thereof;

FIG. 9 is a partially enlarged view of the area labeled 9 in FIG. 2.

FIG. 10 is a perspective view of another embodiment of a light holder according to my new design;

FIG. 11 is a bottom perspective view thereof including an enlargement;

FIG. 12 is a left side view thereof;

FIG. 13 is a right side view thereof;

FIG. 14 is a front view thereof;

FIG. 15 is a rear view thereof;

FIG. 16 is a top view thereof;

FIG. 17 is a bottom view thereof; and,

FIG. 18 is a view illustrating an environment of use of the light holder of FIG. 10.

The broken lines shown in the drawings illustrate portions of the article. The broken lines shown in FIG. 18 depict environmental structure; all broken lines form no part of the claimed design. The broken lines in an alternating dot-dash pattern represent borders of the partially enlarged FIG. 9 and forms no part of the claimed design.
